TUBING SLIDE CLAMP

Armand Al Zeddes, Schaumburg, Ill., assignor to Abbott Laboratories, North Chicago, Ill.

Filed Apr. 12, 1973, Ser. No. 350,558

Term of patent 14 years

Int. Cl. D24—04, 99

U.S. Cl. D16—1 R

FIG.1

FIG.2

FIG.3

FIG.4

FIG.5

FIG.6

FIG. 1 is a perspective view of a tubing slide clamp showing my new design;

FIG. 2 is a top plan view;

FIG. 3 is a side elevational view;

FIG. 4 is a front elevational view as viewed along the line 4—4 of FIG. 3;

FIG. 5 is a rear elevational view as viewed along the line 5—5 of FIG. 3; and

FIG. 6 is bottom plan view.

I claim:

The ornamental design for a tubing slide clamp, substantially as shown and described.
